UNITED STATES PATENT OFFICE.

STEPHEN TEEPLE, OF CHICAGO, ILLINOIS.

ARCH-HOLDER.

No. 853,841.

Specification of Letters Patent.

Patented May 14, 1907.

Application filed June 30, 1906. Serial No. 324,224.

To all whom it may concern:

Be it known that I, STEPHEN TEEPLE, a citizen of the United States, residing at Chicago, in the county of Cook and State of Illinois, have invented new and useful Improvements in Arch-Holders, of which the following is a specification.

This invention is a holder or clamp for arches, particularly for furnace arches or crowns.

It comprises a metal frame provided with plates and adjusting screws at its ends and means for clamping or securing the brick within the same. This secures the bricks more firmly together than can be accomplished in the usual manner, and thus in furnace construction, makes the bricks less liable to burn, crumble or drop out and also makes the fire arch more durable and lasting. In such construction several of the clamps are employed and the bricks are clamped in sections, to suit the length of the furnace.

In the drawings, Figure 1 is a side view of the device, showing the clamp holding the bricks. Fig. 2 is a cross section of a furnace arch and walls. Fig. 3 is a top plan view.

Referring specifically to the drawings, 10 are two segmental spaced bars of iron or other suitable material, which span the arch. 30 x are the bricks and x^1 are recesses in the upper part of the side walls for supporting the crown or arch.

11 are end plates extending across between the ends of the bars 10, and having lugs 11^a through which a bolt 12 passes, having nuts 12^a to hold the same. The lower edge of each plate 11 has a pendant 12^b through which passes a set screw 13 for operating a pivoted plate 14 which is hung from the bolt 12, between the ends of the bars 10 by hinges 14^a through which the bolt 12 passes. Two

of the plates 14, one at each end, are employed and when the bricks are placed between the same, the set screws 13 tighten the same and hold the bricks firmly in place. 45

The construction permits the quick setting or repair of the arch. No mortar is necessary. When the bricks burn out the clamps are loosened, allowing the bricks to drop out and a new set to be inserted. Several sections so constructed will be placed beside each other to form the complete arch. The recesses in which the clamps at the ends of the bars are set cause them to be protected from the fire. 50

I claim:

1. A support for arches formed of bricks or blocks, comprising a pair of parallel curved bars which span the arch and have connecting cross pieces with depending portions; at 60 the ends, bolts between the bars at each end, within said cross pieces, plates swinging upon said bolts and bearing against the end blocks, and clamping screws between the depending portions of the cross pieces and the plates. 65

2. The combination with side walls having recesses in the top thereof, and an arch of bricks extending over the space between the walls, of a curved bar spanning the arch above the bricks, and clamping devices at the 70 ends of the bar and in the recesses, bearing against the end bricks, to bind the arch together the inner walls beside the recesses being extended upwardly toward the bricks, to protect the clamping devices from the fire. 75

In testimony whereof I have signed my name to this specification in the presence of two subscribing witnesses.

STEPHEN TEEPLE.
